UNITED STATES PATENT OFFICE.

HARRY JOSEPH HICK, OF ALLIANCE, OHIO, ASSIGNOR TO THE MCCASKEY REGISTER COMPANY, (INCORPORATED IN 1914,) OF ALLIANCE, OHIO, A CORPORATION OF OHIO.

FILING APPLIANCE.

1,299,725.

Specification of Letters Patent.

Patented Apr. 8, 1919.

Application filed August 6, 1917. Serial No. 184,608.

To all whom it may concern:

Be it known that I, HARRY JOSEPH HICK, a citizen of the United States, residing at Alliance, in the county of Stark and State of Ohio, have invented certain new and useful Improvements in Filing Appliances, of which the following is a specification.

The invention relates to a filing appliance for sales bills and other similar papers in which a plurality of bill holders are operatively mounted upon a suitable table or base for swinging either separately or collectively into upright or reclined position for giving access to the filing faces of the holders; and the object of the improvement is to provide a movable abutment for the rearmost holder of the series, which will oscillate to and fro with the operation of one or more holders so as to sustain the upright holders in a substantially vertical position.

Further objects of the improvement are to mount the movable abutment in such a manner that the weight of the upright holders will not only tend to hold them in upright position but will serve to counterbalance the weight of the holders which are being operated from upright into reclined position and vice versa; and also in such a manner that the abutment may be adjusted to accommodate the addition or subtraction of a considerable number of holders to or from the series without changing any other parts of the appliance.

These objects of the invention and other ancillary advantages are attained by the construction, mechanism and arrangement illustrated in the accompanying drawings, forming part hereof, in which—

Figure 1 is a front elevation of the filing appliance showing the bill holders in normal upright position upon a table and a surrounding case or cabinet;

Fig. 2, is a side elevation of the filing appliance with the upper part of the case broken away, as on line 2—2, Fig. 1, showing the series of bill holders in normal upright position;

Fig. 3, a similar view showing a considerable number of the bill holders operated forward into reclined position;

Fig. 4, a detached perspective view of the bill holders showing the controlling pin protruding from the hinged end of an intermediate holder;

Fig. 5, a detached perspective view of one bearing bracket; and

Fig. 6, a fragmentary perspective view of the abutment carrier guideway.

Similar numerals refer to similar parts throughout the drawings.

The series of bill holders are hinged together at their lower rear ends by means of the ears 2 and the pintles 3 in a well known manner, and the pintles 3' of the forward hinge ears 2' of the foremost holder are mounted on the bearing brackets 4 suitably secured on the table 5 formed in the base 6 of the filing appliance. The rear wall 7 and the rear parts of the side walls 8 of the base are preferably extended upward to form a case or cabinet for normally receiving and shielding the bill holders when in normal upright position, as shown in Figs. 1 and 2.

The abutment carrier 9 is swung upon the pivots 10 at the upper ends of the parallel links 11, which links are supported at the lower ends by the pivots 12 mounted in the bearing plates 13 secured to the floor of the case, there being a pair of parallel links in each side of the case at the sides of the bill holders.

The abutment rollers 14 are mounted on the inner side of the side walls 15 of the abutment carrier 9, and these rollers are preferably carried upon pivot pins 16 secured in one of the series of spaced apertures 17 provided in a row from front to rear in the upper ends of each side wall 15 of the abutment carrier; which rollers form an abutment for the rearmost holder 1 of the series, as shown in Figs. 2 and 3.

The upright guideway 18 is provided at the lower part of the forward edge of each side wall 15 of the abutment carrier 9, which guideways may be in the form of channels 19 shaped along the forward edges of the flanges 20 suitably secured to the side walls of the carrier; and the controlling pins 21 extending laterally each way from the hinged end of one of the bill holders 1^a, referred to herein as the controlling holder, extend into the guideways 18 for operating the carrier to and fro as one or more of the holders in front of and including the controlling holder, are operated from one position to another.

The parts are so proportioned and arranged that when the bill holders are in up-

right position they are supported solely by the forward pintles 3' of the foremost holder upon the bearing brackets 4, and by the abutment of the rearmost holder against the 5 rollers 14 mounted on the side walls 15 of the carrier 9; and that the carrier in turn is supported solely upon the pivots 10 at the upper ends of the links 11, the relative position of which being determined by the operation of 10 the controlling pin 21 on the hinged end of one of the holders in the guideways 18 on the sides of the carrier; and finally that the fulcrum pivots 12 for the lower ends of the parallel links are positioned far enough forward 15 so that the links will be inclined slightly rearward when the controlling holder has been rotated forward into reclined position from which position their upper ends will swing rearward as the controlling holder and one or more of the 20 holders in front thereof are rotated into upright position.

When all the holders are in upright position, it is evident that when the controlling holder or one or more of the holders in front thereof, are swung forward into reclined position, the controlling pins 21 will be carried upward and forward with the hinged end of the controlling holder and in so doing 25 these pins will slide upward in the guideways 18, thus moving the carrier forward and upward by a swinging of its supporting links, which movement carries the abutment rollers upward and forward so 30 that they will always support and sustain the rearmost holder in substantially upright position; and it is obvious that the upright holders will always be supported solely by the forward pivot of the foremost upright 35 holder, and by the bearing of the rearmost holder upon the abutment roller, so that the weight of the upright holders always tends to rotate the same rearward upon the forward pivot of the foremost holder, which is 40 known as the "gravity" operation in appliances of this kind.

It is also evident that the weight of the upright holders will tend to counterbalance the weight of the holders which are being 50 rotated from an upright into a reclined position until the operated holders approach the reclined position and the upper pivot of the foremost reclined holder is carried directly above the lower pivot thereof, which is in 55 front of the line between the axis of said lower pivot and the abutment roller; in which position the weight of the upright holders has no tendency to counterbalance the weight of the reclined holders or to rotate them rearward.

By providing the abutment carrier with abutment rollers thereon adjustable into various positions forward and rearward of the carrier; and by controlling the movements 65 of the carrier by operating means associated

with one of the intermediate holders, it is evident that one or more holders in rear of such intermediate holder can be added or subtracted from the series by merely shifting the abutment rollers rearward or forward as the case may be, and without affecting the operation of the appliance as a whole.

Such a construction and arrangement of the appliance permits a customer having a 75 limited trade to purchase a filing appliance with a limited number of holders, say eight holders adapted to carry 160 accounts by the spring clips 22, as shown in the drawings; to which may be added from time to 80 time, one or more additional holders, each carrying 20 additional accounts as may be necessary or desirable to accommodate the growth of the business.

I claim:

1. A filing appliance including a series of hinged holders, a pivotal support for one end holder, a movable carrier having an abutment adjustable thereon for the other end holder, there being an upright slideway in the carrier and a coöperating slide pin on one of the holders.

2. A filing appliance including a series of hinged holders, a pivotal support for one end holder, a movable carrier having an 95 abutment for the other end holder, there being an upright slideway in the carrier and a coöperating slide pin on one of the intermediate holders.

3. A filing appliance including a series 100 of hinged holders, a pivotal support for one end holder, a movable carrier having an abutment for the other end holder, there being an upright slideway in the carrier, and a coöperating slide pin on the hinge bar 105 of one of the intermediate holders.

4. A filing appliance including a series of hinged holders, a pivotal support for one end holder, a pair of parallel links pivoted at their lower ends at each side of the 110 holders, a pendent carrier pivoted to the upper ends of the links and having an abutment for the other end holder, an upright slideway in the carrier, and a coöperating slide pin on one of the holders.

5. A filing appliance including a series of hinged holders, a pivotal support for one end holder, a pair of parallel links pivoted at their lower ends at each side of the 120 holders, a pendent carrier pivoted to the upper ends of the links and having an abutment for the other end holder, an upright slideway in the carrier and a coöperating slide pin on one of the holders, the links being inclined rearward in the foremost position of 125 the carrier.

6. A filing appliance including a series of hinged holders, a pivotal support for one end holder, a pair of parallel links pivoted at their lower ends at each side of the hold-

ers, a pendent carrier pivoted to the upper ends of the links and having an abutment for the other end holder, and operating means between one of the holders and the carrier for controlling the movement of the carrier.

7. A filing appliance including a series of

hinged holders, a pivotal support for one end holder, a movable carriage having an abutment adjustable thereon for the other 10 end holder, and means actuated by the operation of the holders for controlling the movement of the carriage.

HARRY JOSEPH HICK.
